UNITED STATES PATENT OFFICE.

HORACE LEOPOLD TUCKER BUCKLE, OF IVER HEATH, ENGLAND, ASSIGNOR TO VICTOR TALKING MACHINE COMPANY, A CORPORATION OF NEW JERSEY.

WINDING DEVICE FOR TALKING MACHINES.

Application filed March 18, 1927, Serial No. 176,519, and in Great Britain April 9, 1926.

This invention relates to improvements in talking machines and in particular to improvements in the means for winding the spring motors thereof.

- 5 In talking machines of the smaller type, such for example as portable talking machines, it is desirable that the machine as a whole should be as light as possible and that it should be of a convenient size and 10 shape. In a portable machine in particular it is desirable that the machine should be of small height approximating to the shape of an attaché case, so that it can be easily carried.
- 15 When the motor of a machine of this type has to be wound up and the winding key is inserted horizontally at the side or front of the machine, either the machine must be brought to the edge of the table or other 20 support on which it rests in order that the key may be turned, or else the winding key must have a very short crank so that the handle of the key does not strike the table, and a short crank makes winding difficult.
- 25 According to the present invention the motor is so constructed that the winding key is inserted not horizontally but pointing obliquely downwards. This has the advantage that additional room is given for the 30 handle of the key to be turned and has the further advantage that the machine is pressed slightly downwards on to its support and the machine is less inclined to move about on its support as the winding key is turned.
- 35 The winding key socket with which the key is engaged is mounted to lie obliquely to the top plate of the motor and this socket may be in one piece with the worm member which 35 engages a worm wheel mounted on the ar- 40 bour of the driving spring.

The invention is illustrated by way of example in the accompanying drawings in which,

Fig. 1 is a plan view of part of a portable 45 talking machine to which the invention has been applied, the turntable, motor board and motor top plate being shown partly cut away for the sake of clearness.

Fig. 2 is an end elevation on the line A—B 50 of Fig. 1, the winding key being shown in position.

Fig. 3 is a view on an enlarged scale of the member engaged by the winding key, and

Fig. 4 is a view also on an enlarged scale

of the bearing for the member shown in 55 Fig. 3.

Referring to the drawings 1 is the usual casing, 2 the motor board and 3 the motor suspended from the motor board 2 by suitable bolts 4. The motor 3 is adapted to lie 60 horizontally in the machine in the usual way and in the case illustrated the amplifying horn 5 encircles the motor. The horizontal top plate 6 of the motor has formed in it, an inverted channel portion 7 running 65 obliquely downwards from the outside (see Fig. 4).

Within this channel is secured a barrel 8 by means of rivets 9 for example. The barrel is adapted to form a bearing for a combined winding key socket and worm member 10. The member 10 is furnished at one end with a threaded recess 11 for reception of the end of the winding key 12 and at the other end with a worm screw 13 which engages with a worm wheel 14 on the spring arbor 23. The worm threads on the member 10 may conveniently be six in number and they engage the worm wheel 14 through a horizontal slot 16 in the side of the barrel 8. 70 The end of the member 10 is of reduced section and extends through an aperture in the end of the barrel 8, and it is secured in position by the insertion of a spring ring 17 in a shallow annular recess 18 in the end 75 of member 10.

Between the larger end of member 10 and the interior surface of the barrel is coiled a spring 19 one end of which passes through an aperture in and is anchored to the barrel 8 by a screw 20. This coil spring 19 when the winding key 12 is turned in the motor winding direction slightly unwinds to permit free rotation of the key but when the key is released the spring 19 tightens around 80 it and holds it fast against rotation in the reversed direction.

The spring 19 fits sufficiently closely around the outer end of member 10 and within the barrel 8 to form a bearing for the 85 outer end of the shaft.

The spring drum 21 may be mounted in the ordinary manner between the top and bottom plates 6 and 22 of the motor 3 the spring arbor 23 lying vertically, and the 90 worm wheel 14 thereon, horizontally.

The winding key may of course engage with the member 10 in any known or suit-

able manner other than by its threaded end engaging the threaded recess 11.

By these means a light and inexpensive motor can be provided, with a winding key 5 that can be inserted pointing obliquely downwards from the side of the machine. In the side of the machine is provided the usual aperture or slot 24 for the key 12 to be passed through to engage with the key socket 10 et 11.

I claim:

1. In a talking machine, a spring motor, a casing surrounding the motor, and a winding shaft for the motor journaled near the top of the casing and extending obliquely downward to the motor.
2. In a talking machine, a spring motor comprising end plates and a spring arbor mounted therein, a bearing in one end plate 20 extending obliquely toward the spring arbor, and a winding shaft for the spring arbor mounted in said bearing.
3. In a talking machine, a spring motor comprising top and bottom plates and a 25 spring arbor mounted therein, a bearing in the top plate extending obliquely downward toward the spring arbor, and a winding shaft mounted in said bearing.
4. In a talking machine, a spring motor 30 comprising top and bottom plates and a spring arbor mounted therein, a bearing in the top plate extending obliquely downward toward the spring arbor, a winding

shaft mounted in said bearing, and gearing connecting the winding shaft with the 35 spring arbor.

5. In a talking machine, a spring motor comprising top and bottom plates and a spring arbor mounted therein, said top plate having an oblique channel there-through, a bearing mounted in said channel and extending adjacent the spring arbor, a winding shaft in said bearing and gearing connecting said shaft and arbor.

6. A portable talking machine comprising 45 a cabinet, a spring motor therein, a winding key for the motor having a crank throw at least equal to the height of the cabinet, and a mounting connection for the key arranged oblique to the cabinet so that the handle of 50 the key never extends below the bottom of the cabinet.

7. A portable talking machine comprising a cabinet, a spring motor therein, a winding key for the motor having a crank throw at 55 least equal to the height of the cabinet, and a mounting connection for the key arranged so that the shank of the key extends obliquely downward through the side of the cabinet at such an angle that the handle of the key 60 is always above the level of the bottom of the cabinet.

In testimony whereof I have signed my name to this specification.

HORACE LEOPOLD TUCKER BUCKLE.
